UNITED STATES PATENT OFFICE.

HENRY P. GONSOULAND, OF OAKLAND, CALIFORNIA.

TOILET FOR RAILWAY-CARS.

1,297,147.

Specification of Letters Patent. Patented Mar. 11, 1919.

Application filed January 19, 1918. Serial No. 212,656.

To all whom it may concern:

Be it known that I, HENRY P. GONSOULAND, a citizen of the United States, residing at Oakland, in the county of Alameda and State of California, have invented cer-

5 tain new and useful Improvements in Toilets for Railway-Cars; and I do hereby declare the following to be a full, clear, and exact description of the invention, such as

10 will enable others skilled in the art to which it appertains to make and use the same.

This invention relates to a toilet device particularly designed for use upon portable cars, such as railway passenger cars, inter-

15 urban street cars, street railway cars, or automobiles, and the primary object of the invention is to provide a toilet including the usual type of bowl and an auxiliary re-

ceptacle which is positioned beneath the 20 bowl for receiving material therefrom, which receptacle has its delivery opening normally closed by a suitable pivotally mounted member carried by a shaft to which

25 shaft is connected a lever for rocking the shaft to move the receptacle closure into open or closed position to permit the emptying of the contents therefrom and further to provide means connecting the rockable shaft and the trap door of a passenger rail-

30 way car whereby the shaft can not be rocked for moving the receptacle closure into an open position when the trap door is raised for permitting passengers to alight from the car or enter the car.

35 A further object of this invention is to provide a valve structure which is positioned within the receptacle, near its upper end for closing the opening between the bowl and the receptacle to hide from view

40 the contents of the receptacle which valve mechanism includes means operable under the weight of a person sitting upon the bowl to open the valve structure to move the closure member out of the path of the com- 45 municating opening between the bowl and the receptacle.

With the foregoing and other objects in view, this invention consists in such novel features of construction, combination and 50 arrangement of parts as will be hereinafter more fully described, illustrated in the accompanying drawings and claimed.

In describing the invention in detail, reference will be had to the accompanying 55 drawings, wherein like characters are used

to designate like and corresponding parts throughout the several views and in which:

Figure 1 is a fragmentary view of a railway passenger car showing the invention applied thereto.

60

Fig. 2 is a fragmentary view illustrating the receptacle and looking at the same from a point at right angles to the illustration of Fig. 1.

Fig. 3 is a fragmentary sectional view 65 through the upper portion of the receptacle showing the improved valve which is positioned therein.

Fig. 4 is a sectional view through the receptacle illustrating the improved valve, in 70 end elevation and illustrating in section a fragment of the car floor and the ordinary bowl.

Fig. 5 is a horizontal section taken on the line 5—5 of Fig. 4.

75

Fig. 6 is a fragmentary end elevation of the hopper showing the manner of connecting the two sections which form the valve.

Referring more particularly to the drawings, 1 indicates a fragment of an ordinary 80 railway passenger car having a floor 2 and a trap door 3 which is lowered when the car is in motion over the steps 4 and which trap door is raised, when the car stops at a station, to permit passengers to board or 85 alight from the car.

The improved toilet device is positioned in the car in the usual place and it includes a bowl 5 of the usual construction having a hinged wooden seat 6. The bowl 5 empties 90 through an opening 6^a in the floor 2 of the car into a receptacle 7. The receptacle 7 is attached to the under surface of the floor 2 in any suitable manner and it has a dispensing or outlet opening 8 formed in the 95 center of the bottom thereof. The opening 8 is normally closed by a closure structure 9, comprising a plate 10 having a rubber gasket 11 carried thereby, the upper surface of which is convex as clearly shown in Fig. 100 4 of the drawings. The upper convex portion of the gasket 11 projects into the receptacle 7 and prevents the formation of shoulders on which any particle of the material might cling.

The closure plate 10 has ears 12 formed thereon and extending rearwardly therefrom which ears are connected to a rock shaft 13. The rock shaft 13 is rockably supported by suitable hangers 14 which depend 110

from the under surface of the bottom 2 of the car. The rock shaft 13 has a collar 15 mounted thereon from which extends radially a pair of arms 16 and 17. The arm 17 5 has a counterbalancing weight 18 mounted thereon for moving the closure structure 9 into a closing position. The arm 16 has a hand lever 20 connected thereto by a pin 21 which extends through a slot 22 formed in 10 the lower end of the lever. When the hand lever 20 is rocked, it will rock the rock shaft 13 and move the closure members 9 either into an open or closed position.

A staple or eye 23 is attached to the lever 20 near its lower end, and a chain 24 15 is connected to the eye 23 and to the trap 3, as shown at 25, so that when the trap door 3 is in a raised position, the chain 24 will be held taut for preventing pivotal 20 movement of the lever 20 and consequently locking movement of the rock shaft 13, thereby preventing the moving of the closure member 9 into an open position when the car 1 is at a station.

25 A pipe 26 has communication with a bowl 5 and with a water tank for flushing the bowl. The pipe 26 has an extension 27 formed thereon upon the upper end of which a spigot 28 is mounted which controls the 30 flow of water into a wash basin 29. The discharge from the wash basin 29 is through a pipe 30 into the bowl 5 so that the refuse water from the bowl 29 will pass into the bowl 5, through this bowl into the receptacle 35 7 where it will be retained until the lever 20 is moved for rocking the shaft 13 to move the closure member 9 into an open position.

The plate 40 is positioned within the receptacle 7 at the upper end of the same and 40 the plate 40 is adjustably connected to the receptacle by means of depending ears 41 which are arranged in pairs and formed upon the plate 40 and bolts 42 which extend through the receptacle 7 between each facing 45 pair of the ears 41.

A pair of angled brackets 43 are attached to the inner surface of the receptacle 7 and they have valve members 44 and 45 pivotally connected thereto. The valve members 44 50 and 45 are formed in sections of a sphere, and the edge of the valve member 44 is bent to overlap the meeting edge of the valve member 45, as shown at 46. The valve members 44 and 45 are connected through the 55 medium of suitable fastening members 47 to a hinge structure 48 which hinge structure is in turn pivotally connected by means of pins 49 to the angled brackets 43. The hinge 48', which is positioned at one end of the 60 valve member, has a pair of pins 50 and 51 carried thereby which ride in slots 52 and 53. The slots 52 and 53 are formed angularly in an upstanding plate 54, which plate is attached to a substantially semi-circular 65 metal band 55. The band 55 is pivotally con-

nected, by means of pins 56 and slots 57, to brackets 58 which brackets 58 are supported in any suitable manner within the receptacle 7. A socket member 59 is attached to the outer surface of the circular iron 55 outwardly from the plate 54 and it is provided with an opening 60 through which the lower end of a rod 61 extends. The rod 61 projects upwardly through an opening 62 formed in the plate 40 and through an opening 63 70 formed in the floor 2 and its upper end is positioned in engagement with the under surface of the hinged seat 6 so that when a person sits upon the hinged seat, the weight of the person will move the seat 80 downwardly into engagement with the upper end of the bowl 5 and force the rod 61 downwardly which will rock the substantially circular iron 55 upon its pivot and move the plate 54 downwardly, causing the 85 pins 50 and 51 to ride upwardly in the slots 52 and 53 and rock the valve members 44 and 45 upon their pivotal supports, moving the valve members into open position, as indicated in dotted lines in Fig. 4 of the 90 drawings, and will move them out of the path of the opening 6 so as to permit material to pass from the bowl 5 into the receptacle 7. The slots 57 are provided to permit of the necessary movement of the substantially circular ring 55 to allow for the vertical movement of the plate 54 and to prevent binding of the pins 50 and 51 in the slots 95 52 and 53, respectively. The substantially circular bar 55 has weights 63^a attached to 100 the ends thereof which will move the substantially circular member 55 into its normal position, forcing the rod 61 upwardly and slightly raising the seat 6, when the person arises from the seat. The movement of the 105 circular member 55 to its normal position will move the pins 50 and 51 downwardly in the slots 52 and 53 which will move the valve members 44 and 45 into a closed position, as illustrated in solid line in Fig. 4 of the 110 drawings.

From the foregoing description taken in connection with the accompanying drawings the advantages of construction and the method of operation of the improved toilet 115 for railway cars will be readily apparent to those skilled in the art to which this invention appertains and, while in the foregoing description, the principle of the operation of this invention has been described together 120 with various features of construction, it is to be understood that certain minor features of construction, combination and arrangement of parts may be altered to suit practical conditions provided such alterations are comprehended within the scope of what is claimed.

What is claimed is:

1. In a device as set forth, the combination, of a water closet bowl, a wash basin, 130

a refuse receptacle for receiving material from said bowl, and a waste water pipe communicating with said basin and said bowl near the top of the bowl.

5 2. The combination with a railway car including a step protecting trap door, of a water closet bowl, a refuse receptacle for receiving material from said bowl having an outlet opening, a hinged closure for said 10 opening, a lever for operating said closure, means connecting said lever and said trap door to prevent the opening of said closure when said trap door is in a raised position, a wash basin, a waste water pipe communicating with said basin and said bowl near 15 the top of the bowl.

3. In a device as set forth, the combination, of a water closet bowl, a refuse receptacle for receiving material from said bowl, 20 a pair of valve members pivotally connected to the interior of said receptacle and normally closing the communicating opening between said bowl and refuse receptacle, a curved bar rockably supported within said 25 receptacle, a rod connected to said rockable bar and to the seat of said closet bowl, whereby the rod will be moved downwardly under the weight of a person sitting upon the closet bowl to rock said rockable bar, 30 and means connecting said bar and said

valve members for moving the valve members into an open position upon downward movement of said rod.

4. In a device as set forth, the combination, of a water closet bowl, a refuse receptacle for receiving material from said bowl, 35 a pair of valve members pivotally connected to the interior of said receptacle and normally closing the communicating opening between said bowl and refuse receptacle, 40 a curved bar rockably supported within said receptacle, a rod connected to said rockable bar and to the seat of said closet bowl, whereby the rod will be moved downwardly under the weight of a person sitting upon 45 the closet bowl to rock said rockable bar, and means connecting said bar and said valve members for moving the valve members into an open position upon downward movement of said rod, weights attached to 50 said rockable bar for returning the bar to its normal position and moving said valves into a closing position when the person arises from the bowl seat.

In testimony whereof I affix my signature 55 in presence of two witnesses.

HENRY P. GONSOULAND.
